UNITED STATES PATENT OFFICE.

JOSEPH SZAREK, OF LIVERMORE, PENNSYLVANIA.

RAIL-JOINT.

1,342,006.

Specification of Letters Patent. Patented June 1, 1920.

Application filed March 3, 1920. Serial No. 362,976.

To all whom it may concern:

Be it known that I, JOSEPH SZAREK, a citizen of Poland, residing at Livermore, in the county of Westmoreland and State of Pennsylvania, have invented certain new and useful Improvements in Rail-Joints, of which the following is a specification.

The primary object of the invention is the provision of a joint for railway rails providing a substantially unbroken tread surface, alining means for the rails being adapted for compression upon tightening connections between the rails.

A further object of the invention is the provision of a scarf joint for a rail adapted to secure the abutting ends of rails together and locking resilient alining means for the rails simultaneously with the locking of the rails together.

With these general objects in view the invention consists of the novel combination and arrangement of parts hereinafter more fully described in connection with the accompanying drawings in which like reference characters designate corresponding parts throughout the several views.

In the drawings,

Figure 1 is an elevational view of rails connected together after the manner of my invention with parts broken away,

Fig. 2 is a top plan view thereof,

Fig. 3 is a central longitudinal sectional view of the same and

Figs. 4 and 5 are vertical transverse sectional views taken upon lines IV—IV and V—V of Fig. 1.

Referring more in detail to the drawing, I have illustrated two rails 10 and 11 having their adjacent ends complementally formed for attachment together with the rails in longitudinal alinement. The web 12 of each rail is thickened at the end thereof with corresponding sides of the rail ends cutaway forming overlapping end sections 13. Each end section 13 terminates in an oblique face 14 at the end of its tread portion and a corresponding face 15 at the end of the base flange while the intermediate end 16 of the thickened terminal web portion 17 is curved as best illustrated in Fig. 3 of the drawing.

In a similar manner, each tread portion at the inner end of the cutaway portion of the rail has an inclined face 14' and an inclined face 15' for the base flange, the said faces 14' and 15' being normally positioned

substantially abutting the faces 14 and 15 respectively when the rail joint is assembled. The web 12 is provided with a slight notch or groove 18 at the cutaway portion of the 60 rail for receiving the curved end 16 of the thickened web portion 17 of the adjacent rail.

The end section 13 of each rail has a longitudinal socket 19 in the tread portion thereof 65 for holding a coil spring 20 projecting outwardly and into a corresponding socket 21 in the tread of the main portion of the adjacent rail, these springs 20 assisting in maintaining the rails 10 and 11 in their operative longitudinal alinement. Securing bolts 22 are positioned through perforations 23 in the thickened web 17 of one of the rails such as 10, wedging heads 24 upon said bolts being positioned in openings 25 through the 75 thickened web 17 of the adjacent rail 11. An inclined face 26 of each bolt head 25 bears against an inclined face 27 of the opening 25 while nuts 28 are threaded upon the bolts 22 opposite the headed ends thereof. 80

When the springs 20 are placed in position within the sockets 19 and 21, the rails 10 and 11 will be held in longitudinal alinement with the end sections 13 overlapping for temporary purposes. The bolts 22 are 85 then placed in position through the openings 25 and perforations 23 and upon tightening the nuts 28, the rails 10 and 11 will be moved longitudinally for tightening the joint therebetween and compressing the 90 springs 20, such action being accomplished by drawing the wedging heads 24 of the bolts inwardly of the openings 25. A strong joint is provided in which the tread of the rails is substantially unbroken at the 95 point of connection of the rails with the exception of the adjacent diagonal faces 14 and 14' which prevents any bumping of the wheels thereover by reason of its diagonal arrangement. The rail ends are substantially dove-tailed together with the springs 20 serving as dowel pin members and the bolts 22 as adjustable locking means for the joint. 100

While the form of the invention herein 105 set forth is believed preferable, it will be understood that minor changes may be made therein without departing from the spirit and scope of the invention as claimed.

What I claim as new and desire to secure 110 by Letters Patent, is—

1. A rail joint comprising the ends of

- rails complementally formed adapted for overlapping at their web portions, the tread portions of the rails having alining longitudinal sockets, resilient connectors within 5 said sockets and wedging bolts connecting the overlapping web portions of the rail ends adapted for tightening upon the webs simultaneously with the compressing of said resilient connectors.
10. 2. A rail joint comprising complementally formed rail ends having diagonal abutting faces and side cutaway portions whereby the web portions of the rail ends are adapted for flat engagement when the joint 15 is assembled, helical springs connecting the tread portions of the adjacent rail ends when the rails are in substantial longitudinal alinement, said web portions having corresponding perforations and openings 20 therethrough and bolts adjustably secured through said perforations with wedging heads within said openings whereby the rails are longitudinally shifted during the compressing of said springs upon the tightening 25 of the bolts upon the webs.

3. A rail joint comprising complementally formed rail ends having diagonal abutting faces and side cutaway portions whereby the web portions of the rail ends are adapted for flat engagement when the joint 30 is assembled, helical springs connecting the tread portions of the adjacent rail ends when the rails are in substantial longitudinal alinement, said web portions having corresponding perforations and openings 35 therethrough, bolts adjustably secured through said perforations with wedging heads within said openings whereby the rails are longitudinally shifted during the compressing of said springs upon the tightening 40 of the bolts upon the webs, the free ends of the webs of the rails being curved and the web portions of the adjacent rails having vertical grooves adapted for the reception of said curved ends when the joint 45 is assembled and operating nuts threaded upon the unheaded ends of the bolts.

In testimony whereof I affix my signature.

JOSEPH SZAREK.
